UNITED STATES PATENT OFFICE.

HARRY S. DANA, OF SAN FRANCISCO, CALIFORNIA.

DESIGN FOR A FINGER-RING.

SPECIFICATION forming part of Design No. 36,747, dated January 26, 1904.

Application filed December 17, 1903. Serial No. 185,596. Term of patent 3½ years.

To all whom it may concern:

Be it known that I, HARRY S. DANA, a citizen of the United States, residing in the city and county of San Francisco, State of California, have invented a new, original, and ornamental Design for Finger-Rings, of which the following is a specification, reference being had to the accompanying drawings, forming part thereof.

Figure 1 is an edge view of a finger-ring, showing one side of the design. Fig. 2 is a

side view of a ring, partially showing the design upon both sides. Fig. 3 is a top view showing both sides of the design. Fig. 4 is an edge view showing the opposite side to Fig. 1. 15

What I claim is—

The ornamental design for a finger-ring, as shown.

HARRY S. DANA.
